UNITED STATES PATENT OFFICE.

SIMON COOPER, OF BROOKLYN, NEW YORK.

ELECTRICAL SOSTENUTO PIANO.

Refiled for application Serial No. 562,269, filed May 19, 1922. This application filed January 18, 1923.
Serial No. 613,534.

This invention relates to a method and apparatus for initiating or sustaining the vibrations of a sonorous body, as for instance, a piano string, in the production of 5 the characteristic musical tone thereof.

The principal object of the invention is to provide for sustaining or initiating the vibration of a piano string in the production of its characteristic musical tone, with the 10 least possible interference with such free and natural vibration of the string. I have previously devised and demonstrated an electrical sostenuto piano with certain of the 15 electrical contacts located directly on the string and on the vibrating portion thereof, and to do away with mechanical interference with the free vibration of the string in making and breaking contact, I made the contact member carried by the string, and the co- 20 operating contact member, very light, and provided for the slightest possible pressure between them. While this arrangement has been satisfactory, I have, in the course of experiments, found that other arrangements 25 are feasible and practical. In the present invention accordingly I have aimed to control the energization of the electro-magnet which directly affects the string by means of contact members entirely removed from the 30 vibrating portion proper of the string.

Other objects and aims of the invention, more or less broad than those stated above, together with the advantages inherent, will be in part obvious and in part specifically 35 referred to in the course of the following description of the elements, combinations, arrangements of parts, and applications of principles constituting the invention; and the scope of protection contemplated will 40 appear from the claims.

In the accompanying drawings, which are to be taken as a part of this specification, and in which I have shown merely a preferred form of embodiment of the invention, Figure 1 is a partly diagrammatic showing of an arrangement of electro-magnet in connection with a string, sound board, and other parts of a piano, including the application of one form of embodiment of my present invention; Figure 2 is an elevation showing part of a piano structure with an embodiment of my invention applied thereto; Figure 3 is an elevation of a sound board or other resonating member of a piano struc-

ture with a form of embodiment of my invention applied thereto; Figure 4 is a sectional view showing details of another form of embodiment of my invention; Figure 5 is an elevation of the subject-matter of Figure 4; Figure 6 is a view similar to Figure 4, 55 illustrating a modification; Figure 7 is a sectional view illustrating another form of embodiment; Figure 8 is an elevation at right angles to Figure 7; Figure 9 is a view taken on the line 9—9 of Figure 7; Figures 60 10 and 11 show the circuit maker and breaker 20 and 30 more in detail.

Referring to the numerals on the drawings, and particularly to Figure 1, there is shown at 10 a sounding board of a piano. 70 11 indicates a string, and 12 the bridge. 14 indicates the magnet placed in proximity to the string and included in a branch circuit 15, which circuit is normally open, but closed 75 by the depression of piano key 16, which depression brings together contacts 17 and 18, to close the circuit so far as this normal break is concerned. A battery or other generator is indicated at 19, and in practice one 80 battery will serve for a considerable number of magnets 14 and branch circuits 15. The circuit 15 also includes a resilient contact member 20, suitably fixed upon the sounding board 10, or other resonating member constituting a part of or located in operative 85 proximity to the piano; and a co-operating contact member which may be in the form of a carbon button for instance, indicated by the reference character 21. In Figure 1, I 90 have shown two sets of these co-operating contact members 20 and 21, and it will be understood that each one is in a branch circuit that includes an electro-magnet for a particular string, controlled by a particular key 16, though all of these circuits may be 95 energized from the same battery 19 in a well-known manner.

Assuming that the key 16 has been depressed, resulting in the striking of the string 11 by hammer 22, the string 11 will be set in vibration, causing characteristic vibration in the sounding board 10. I have found that by locating the contact button 21 at some point on the sounding board empirically determined with reference to the vibrations set up in the sounding board by the characteristic vibrations of a particular string, the contact 21 will be moved rel-

atively to the cooperating contact 20 with which it is normally in contact at a moment when the portion of that string opposite its magnet is at a particular point in the path 5 of movement of the string. This particular point in the path of movement of the string is such that the pulsation of current in the magnet, resulting from the cooperation between the vibrating contact 21 and the resil- 10 ient contact 20 which bears against it, will energize the magnet to exert a pull on the string at a moment when the portion of the string opposite the magnet is moving toward the latter. That is to say, the cooperation 15 of the contacts to cause a pulsation of current in the magnet circuit is empirically fixed to occur at a definite moment which results, allowing for the time it takes for the magnet to respond to the pulsation, in 20 the magnet pulling upon the string when the string is moving toward the magnet. Thus the desired true musical tone is obtained from the string, without interfering at all with the amplitude of vibration or with the 25 natural motion of the vibrating string, since none of the controlling contacts are carried by the string or in direct physical contact therewith.

I prefer that the resilient contact member 30 20 should bear against contact member 21 with a very light pressure, so that as the sounding board vibrates in response to the vibrations of the particular string appropriated to the particular button 21, the movements of the button 21 as it travels with the 35 vibrating sounding board will break or vary contact between the button and the contact member 20 and consequently in step with the energizations of the magnet 14. It will be evident that the amount of pressure exerted by the contact member 20 may be 40 varied and adjustable in accordance with conditions surrounding the particular string, but the important thing is that every individual string in its vibration will induce 45 characteristic vibrations in the sounding board or other resonating member, and that by exploration such point may be found, where the contact member 21 is to be located 50 for the securing of the desired tone in the string when the latter is vibrated. Instead of ranging over the sounding board and locating a desirable point for the contact member 21 appropriated to each individual 55 string, I may place upon the sounding board a collection of sets of contact members 20 and 21, then a test is made for each individual string by connecting it with first one and then another of these sets of contacts, 60 until that one is found which gives the desired tone results. And in Figure 3 this idea is carried still further, by mounting a large number of sets of contacts 20 and 21 upon a supplemental sounding board 24, 65 which will be attached or located in prox-

imity to the piano. For each string one of the sets of contact members 20 and 21 will have to be found by test as giving the desired tone results. It may be found in practice that one set of contacts 20 and 21 will 70 answer for more than one string.

In Figures 7, 8 and 9 the same idea is carried out, that is to say, there is a sounding board or auxiliary resonating member 10, which carries a plurality of resilient contact members 20, each of which is appropriated to a particular one or plurality of strings. These several contact members 20, instead of engaging with individual co-operating contacts 21 as in the forms of the invention previously described, all engage 75 with a common conductor or contact member 25, which is in the form of a vibratile reed firmly secured at one end to the sound board, preferably upon a block 26 secured to 80 the sounding board. It will be observed that each contact member 20 in Figures 7, 8 and 9 engages at a different point on the vibratile reed 25. What these particular points are will be determined by experiment, 85 that is to say, when a particular contact member 20 has been appropriated to a particular string, that contact member 20 will be moved, bringing its contact end to bear 90 upon different portions of the reed 25 until 95 a point is found where the string gives satisfactory tone results upon energization of its magnet by depression of its key 16. The contact member 20 is then fixed in the position so discovered as by means of a 100 screw 27. In this embodiment also I have found that a single point in the reed 25, engaged by a single contact member 20 may control more than one string. The vibrations of the reed 25 will be in synchronism 105 with those of the sounding board or other resonating member to which the reed is attached.

Referring to Figures 4, 5 and 6, 10 indicates the sounding board as before, and 12 110 the bridge. The anchorage of the string is indicated at 28. As is well known, that part of the length of the string between the bridge 12 and the anchorage 28 is not concerned in the production of the tone of the 115 string, that is to say, its vibrations are negligible so far as tone production is concerned. However, there is a certain amount of vibration in this short length of the string between the bridge and the anchorage, and this vibration is necessarily synchronous 120 with the vibrations of the main length of the string. Accordingly, in Figures 4 and 5 I show a contact member in the form of a wire 29 fastened to the bridge 12, in proximity to and in contact with the string 11. Of course this wire 29 may be fastened to the string itself at the point where the latter bears on the bridge. The cooperating 125 contact member may be a coiled spring 30 130

supported by a plate or bar 31 of non-conducting material rigidly fastened to the piano frame at a proper distance from the string 11. The wire 29 extends down inside 5 the coil 30, and the end of the wire 29 is caused to bear against the inner circumference of the coil at such point around said circumference as will bring about the true synchronism between the energization of the 10 magnet and the phase of vibration of the string. Of course both the wire on the bridge and the coil 30 will be in circuit with a magnet, the same as contacts 20 and 21 described with reference to Figure 1 and 15 the general operation is substantially the same as that already described with reference to Figure 1.

In Figure 6 there is shown a modification, to the extent that the contact wire 29 20 instead of being fixed in position is adjustable lengthwise of the portion of the string 11 between bridge and anchorage, by means of a sleeve or loop attaching portion 32 embracing the string, and held in fixed 25 relation thereto by means of a clip or set screw or soldering or otherwise. By moving the wire 29 up and down on the string a point may be found where the greatest musical value of the string 11 is obtained. This 30 adjustment may be made in addition to the adjustment of the point of contact of the end of the wire 29 with the inner circumference of the coil 30, as previously described.

35 It will be evident that in all the forms of the invention described the full and free vibration of the piano string is not interfered with at all, while at the same time provision is made for securing the best tone values 40 from the strings by proper co-ordination of the energization of the magnet with the vibration of the string.

In all forms of the invention herein described the piano string sets up characteristic 45 vibrations in a sounding board or other vibratile member which is preferably associated with the piano but not directly associated with the vibrating sound-producing portion of the string. A magnet is provided, whose 50 energization results in a pull upon the string. The vibrations induced by the string at an empirically determined point on the vibratile member are caused to control the pulsations of current in the magnet circuit, and 55 this point is such a one that the pulsation energizes the magnet to cause a pull upon the string when the string is moving towards the magnet.

This application is filed as a substitute for 60 my application Serial No. 562,269, filed May 19, 1922.

I claim:

1. The herein described method of vibrating the strings of a musical instrument which 65 comprises producing pulsations of current in

magnets for vibrating the respective strings and locating circuit controllers for the respective magnets on vibratile portions of the instrument at empirically predetermined points which vibrate in a definite time 70 relation with the strings which are actuated by the respective magnets, and in accordance with such empirical determinations locating different magnets for coaction with different strings in such manner that a controller having a vibration-location causing its magnet to have a more advantageous coaction with one string than another, will have its magnet arranged to coact with the first of the two last-mentioned 80 strings.

2. The herein described method of vibrating the strings of a musical instrument which comprises producing pulsations of current in magnets for vibrating the respective strings and locating circuit controllers for the respective magnets on the sounding board of the instrument and at empirically predetermined points thereon which naturally vibrate in a definite time relation with 85 those strings which are actuated by the respective magnets, and in accordance with such empirical determinations locating different magnets for coaction with different strings in such manner that a controller having a vibration-location causing its magnet to have a more advantageous coaction with one string than another, will have its magnet arranged to coact with the first of the two 90 last-mentioned strings. 95

3. The herein described method of vibrating the strings of a musical instrument which comprises producing pulsations of current in magnets for vibrating the respective strings, determining by exploration those points on 100 vibratile portions of the instrument which differentially vibrate in such manner that one point has a more favorably timed vibration with one particular string than another, and locating circuit controllers for the magnets of the respective strings on the critical points ascertained in accordance with such favorable vibration-relation characteristics. 105

4. The method of operating a sostenuto piano which comprises locating circuit controllers on the sound board of the instrument at empirically predetermined points thereon which differentially vibrate in such manner that one point has a more favorable 110 timed vibration with one particular string than another, and controlling the magnets for the respective strings from the circuit controllers, said controllers being located so that magnets for different strings are controlled by controllers at points having such favorable vibration-relations with said strings. 115

5. The method of operating a sostenuto piano which comprises locating a circuit controller on a vibratile portion of the piano at that one of two possible points which 120 125 130

vibrates in the more favorable time relation with a particular string and controlling a magnet for vibrating that string by said thus-located circuit controller.

6. The method of operating a sostenuto piano which comprises determining empirically upon that one of several vibratile portions of the instrument which vibrates naturally in the more favorable time relation 10 with a given string and fixing a circuit controller for the actuating magnet of that particular string at such point.

7. The method of operating a sostenuto piano which comprises locating that one of 15 a plurality of portions of the sound board of the instrument which vibrates naturally in the more favorable time relation with a particular string and controlling the actuating magnet for that string by a circuit controller mounted on that portion of the sound board.

8. The method of operating an electro-magnetic sostenuto device for a piano string which consists in causing a pulsation of current in a magnet for vibrating the string at 20 a moment of time such that the consequent energization of the magnet will occur when the string is moving towards the magnet and timing the initiation of such pulsation by the vibration of a selected one of two points on a sounding board associated with the string, such selected point being that one having naturally a more favorably timed vibration, than the other point, relative to the vibration 25 of said string.

9. The method of operating an electro-magnetic sostenuto device for a piano string which consists in causing a pulsation of current in a magnet for vibrating the string at 30 a moment of time such that the consequent energization of the magnet will occur when the string is moving towards the magnet and controlling the initiation of such pulsation by the vibration of a vibratile member 35 of the piano other than said string, by locating a control for the magnet circuit upon, and making it subject to the vibrations of, a particular one of two points on said vibratile member, empirically determined as the

more favorable point for the purpose described.

10. In a piano, the combination with the sound-producing strings and an element vibrated thereby, of electro-magnetic means for vibrating a string, including a circuit 55 and cooperating contacts therein, one of said contacts being carried by said vibrating element at that one of two points where the vibrations of said element are more favorably timed with those of the string. 60

11. In a piano, the combination with the sound-producing strings and an element vibrated thereby, of electro-magnetic means for 65 vibrating a string, including a circuit and cooperating contacts therein, one of said contacts being carried and controlled by said vibrating element of the piano, the latter contact being at that one of two points on said vibrating element whereat the natural vibration of said element is more favorably 70 timed with the vibration of said string.

12. In a piano, the combination with the piano strings and the sound board associated therewith, of magnets for vibrating the different strings and circuit controllers for the 75 several magnets each located on a particular portion of the sound board which vibrates naturally in a definite time relation with the string actuated by the magnet it controls, each of the two points selected for the controller having, as compared with the other, a more favorable vibration-relation with its assigned string. 80

13. In a piano, the combination with the piano strings and a member vibrated thereby, of magnets for vibrating the different strings and circuit controllers for the several magnets located at points on said vibrating member which vibrate in a definite time relation with the strings actuated by the 90 respective magnets which they control, each of the two points selected for the controller having, as compared with the other, a more favorable vibration-relation with its assigned string. 95

In testimony whereof I affix my signature.

SIMON COOPER.
